IGNITION CONTROL

Ira E. McCabe, Chicago, Ill.

Application May 7, 1940, Serial No. 333,815

5 Claims. (Cl. 158—28)

This invention relates to improvements in electrically operated and controlled fluid fuel burning mechanisms for heating systems and more particularly to an ignition device employed therein.

It is desirable each time the system calls for heat and the burner motor delivers fuel to the combustion chamber that an ignition device will be operative to ignite the fuel and prevent delivery of unignited fuel to flood the combustion chamber before ignition takes place.

It is an object of this invention to provide, as a part of the control mechanism, an electrical ignition device so constructed that each time the motor switch is closed the ignition device will be operative, continue in operation for a predetermined period, then become inoperative, and as soon as the motor switch is opened during the normal operation of the system or at any other time, such as caused by a power failure, even momentarily, the ignition device will be placed in position to operate on the next closing of the motor switch.

It is a further object of this invention to so construct the ignition switch and actuating parts forming the improved ignition device that the closing of the motor switch will close a circuit through the ignition switch and ignition switch actuator to open the ignition switch at the close of the ignition period in such a manner that a momentary cessation and resumption of the current during the ignition period, which at times occurs, will not shorten the period of time of the ignition period.

With these and other objects in view, reference is made to the accompanying sheets of drawings which illustrate a preferred form of this invention, with the understanding that detail changes may be made without departing from the scope thereof.

Figure 1 is a view in front elevation showing a preferred form of this invention, illustrating a commercial type of fluid fuel burner heating system in diagram with a wiring diagram of the circuits employed therein.

Figure 2 is a fragmentary enlarged detail view in front elevation of the improved ignition device control and the operating parts thereof, in the position assumed when the burner mechanism is idle.

Figure 3 is a view in end elevation looking toward the left end of Figure 2, omitting the motor switch and motor switch operator.

Figure 4 is a similar view in end elevation, looking toward the right end of Figure 2.

Figure 5 is a view similar to Figure 2, illustrating the position assumed by the parts when the motor switch is closed and the ignition switch still closed when the burner mechanism is starting.

Figure 6 is a view similar to Figure 5, illustrating the position assumed by the ignition switch at the end of the ignition period.

Figure 7 is a view similar to Figure 6, illustrating the position assumed by the parts after the ignition period has been completed and the control is in the normal running position.

In the embodiment of this invention and the heating system illustrated in Figure 1, the motor switch M, the ignition switch I, and the safety switch S are preferably mercury tube switches. Switches M and I are mounted for operation upon a panel P indicated in dot-and-dash lines, while the safety switch S and its operator are shown, in the wiring diagram, as being removed from the panel P. The furnace or heater F is shown with an oil burner of commercial form operatively installed therewith. The oil burner includes a burner motor BM, an ignition transformer IT, connected with the electrodes E arranged in front of the burner nozzle. The operation of the burner motor is controlled by a room thermostat RT of commercial form. The motor switch M is opened and closed by a commercial form of repulsion relay including a stationary primary coil PC and a movable secondary coil SC. The winding of the primary coil PC is always connected in circuit with the commercial line L and L'. The commercial line L 25 is connected to wire 1, which preferably conducts the commercial current through a boiler control BC to the safety switch S and from there through the binding post 2 to one end of the winding of the primary coil PC. The other end 30 of the winding of the coil PC is connected by wire 3 through binding post 4 to the other commercial line L'. The current of the commercial line passing through wire 1 divides at binding post 2 and part of it passes by way of wire 5 through the motor switch M and through binding post 6 and through burner motor BM, and from thence by way of wire 7 to binding post 4 and from thence by way of wire 3 to commercial line L'. The windings of the secondary coil SC are 35 connected by wires 8 through the room thermostat RT and through binding post 9, through the electrical resistance heater RH, forming a part of the commercial device for operating the safety switch S, and through binding post 10. When 40 the system calls for heat and the circuit is closed 45 of the winding of the coil PC is connected by wire 3 through binding post 4 to the other commercial line L'. The current of the commercial line passing through wire 1 divides at binding post 2 and part of it passes by way of wire 5 through the motor switch M and through binding post 6 and through burner motor BM, and from thence by way of wire 7 to binding post 4 and from thence by way of wire 3 to commercial line L'. The windings of the secondary coil SC are 50 connected by wires 8 through the room thermostat RT and through binding post 9, through the electrical resistance heater RH, forming a part of the commercial device for operating the safety switch S, and through binding post 10. When 55 the system calls for heat and the circuit is closed

through the room thermostat the secondary coil is energized and is repelled from the primary coil PC to close the motor switch M. When the room thermostat opens the circuit the coil is de-energized and its weight falls to rest upon the primary coil PC and opens the motor circuit. This is a commercial construction and need not be explained in detail. In order to prevent the heating of the resistance heater RH to open the safety switch S, a shunt circuit is provided by wires 11 passing through a control switch preferably in the form illustrated in this applicant's prior Patent No. 2,162,098 of June 13, 1939, responsive to the presence or absence of a flame at the burner, which, when combustion is established, acts through the wires 11 to shunt out the heater RH.

The construction so far described relates to that part of a commercial system of oil burner controls for the normal starting and stopping of the burner in response to the room thermostat, as well as the stopping of the burner by a safety apparatus upon the absence of the burner flame. In such systems where ignition means are employed for igniting the burner, ignition control devices are generally employed which render the ignition means operative when placing the oil burner in operation and thereafter render the ignition means inoperative after the burner is operating. This invention relates to such ignition control devices and will now be described.

The ignition switch I is connected from commercial line L, through the motor switch M, to the ignition transformer IT by the wire 12 leading from the binding post 6 to which the wire 5 from the motor switch is connected. The current, after passing through wire 12 and the ignition switch I, then passes by the way of wires 13, through a resistance heater 14, to the ignition transformer IT. The current passing through the ignition transformer is connected by wire 15 to wire 7 which returns the current from the motor to the commercial line L'. When the motor switch M is closed to establish the motor circuit, a circuit is also set up through the resistance heater 14, ignition switch I, and ignition transformer. The resistance heater 14 is operatively associated with a strip of bimetallic metal 16, one end of which is fixed to a bracket 17 formed integral with a face plate 18, then bent around the heater 14 so that the free end 19 will be moved in one direction by the heat generated when the current passes through the heater 14 and upon the discontinuance of the current will, upon cooling, move in the opposite direction. This movement of the free end 19 of the bimetallic strip 16 is employed to open the ignition switch I.

The ignition switch I is preferably a mercury tube switch which is mounted upon a rotatable carrier plate 20 so that when the switch is tilted in one direction it will close the circuit therethrough and when tilted in the opposite direction will break the circuit therethrough. This type of mercury tube switch is a commercial article and need not be explained in detail. The carrier plate 20 is rotatably mounted upon the pivot 21 extending between the front plate 18 and the base plate 22, as shown in Figures 1 and 4. The base plate 22, as illustrated in Figure 4, is spaced apart from the panel P by spacing studs 23, which also serve to support core 24 of the repulsion relay including the coils PC and SC. The pivoted ignition switch carrier plate 20 is extended above a bracket extension 25 therefrom, supporting the ignition switch I and is pro-

vided with an arcuate toothed segment 26 concentric with the pivot 21 and is also provided with a tooth 27 extending from the side opposite the ignition switch I below the center of a radius 5 extending from the pivot 21 to the arcuate toothed segment 26. An ignition switch latch is mounted on a pivot 28 extending between the base plate 22 and the front plate 18 at the left and above the ignition switch I.

10 The ignition switch latch is provided with a portion extending to the right of its pivot and above the toothed segment 26 and terminates in a pawl 29 adapted to ride over the teeth of the segment 26 when the carrier plate 20 is rotated 15 to the right upon its pivot 21 and to engage in the teeth and prevent counter-revolution. The latch also includes a portion 30 depending from the end adjacent the pawl 29 and extends below the ignition switch I. The weight of the latch 20 will normally cause the pawl 29 to engage the toothed segment 26. In order to lift the latch so that the pawl 29 is out of engagement with the teeth of the segment 26 to allow the ignition switch to return to its normal closed position 25 when the secondary coil has been de-energized, a latch release in the form of an arm 31 is preferably secured to the upper side of the coil SC and is so arranged in relation to the free end of the depending portion 30 of the latch that 30 when the secondary coil is de-energized and has fallen to rest upon the primary coil, as shown in Figures 1 and 2, the latch release 31 has engaged the lower end of the depending portion 30 to rotate the latch about its pivot 28 to lift the pawl 29 out of engagement with the toothed segment 26. When the room thermostat calls for heat and the secondary coil is repelled to close the motor switch M the latch release 31 is carried 35 out of engagement with the depending portion 30 of the latch so that the latch may rotate about its pivot 28 to engage the pawl 29 with the toothed segment 26, as shown in Figures 5, 6 and 7.

35 The ignition switch I is so mounted on the switch carrier plate 20 that when free to rotate the mercury tube switch will assume its closed position to allow the ignition circuit to pass therethrough when established. In order to rotate the switch carrier plate 20 about its pivot to tilt the ignition switch I to its open position, an actuating plate 32 is mounted on a pivot 33 soldered or otherwise secured to the extremity of the free end 19 of the bimetallic member 16 responsive to the presence or absence of heat 40 in the electrical resistance heater 14. This actuating plate 32 is provided on its under side with a toothed rack 34 adapted to be engaged by the tooth 27 on the carrier plate 20. A slot 35 is provided in the actuator plate above the rack 34, the upper portion of which is adapted to be engaged by stud 36 mounted upon the depending portion 30 of the latch extending through the slot 35 and so arranged that when the latch has been lifted to free the pawl 29 from the toothed segment 26 of the carrier plate, the stud 36 will lift the actuating plate 32 to free the rack 34 from engagement with the tooth 27 upon the switch carrier plate and when the latch release 31 has released the latch to allow the pawl 29 to engage the toothed segment 26, the actuator plate 32 will be allowed to rotate about its pivot 33 so that the rack 34 will be in engagement with the tooth 27 upon the switch carrier plate. The teeth of the rack 34 are so constructed that, when the energization of the

heater 14 is established the free end 19 of the bimetallic member is caused to move toward the right, to engage the teeth of the rack 34 with the tooth 27 to rotate the carrier plate 20 to tilt the ignition switch to the open position, as shown in Figures 6 and 7.

By this construction, it is seen that when the heating system is idle the room thermostat is in the open position as the temperature of the room is satisfied. The parts of this ignition control assume the position shown in Figures 1 and 2. The latch release 31 has rotated the latch about its pivot 28 to lift the pawl 29 out of engagement with the toothed segment 26 upon the switch carrier plate 20 and at the same time, lifted the actuator plate 32 by the stud 36 to lift the rack 34 free of the tooth 27 whereby the weight of the mercury tube switch I rotates the switch carrier plate 20 to support the ignition switch in its closed position.

With the boiler control switch BC and safety switch S closed, a circuit is established to the primary coil PC from the commercial line. When the temperature in the room containing the room thermostat descends below the predetermined degree for which the thermostat is set, the thermostat closes and establishes the circuit through the wire 8 from one winding of the secondary coil through the safety switch resistance heater RH to the other winding of the secondary coil SC. This circuit not only energizes the resistance heater RH of the safety switch, but also energizes the secondary coil, causing it to be repelled from the primary coil to assume the position in starting the burner, as illustrated in Figure 5. The repulsion of the secondary coil SC removes the latch release 31 to allow the latch to rotate about its pivot 28 and engage its pawl 29 with the right end portion of the toothed segment 26 upon the carrier plate 20, and at the same time, drops the actuator plate 32 to engage its rack 34 with the tooth 27 upon the carrier plate 20. The repulsion of the coil SC also rotates the mercury tube switch M in the motor circuit to its closed position whereby a circuit is established by the wire 5 from the binding post 2 through the motor switch M, binding post 6, burner motor BM, and wire 7 to binding post 4 and the operation of the motor is initiated. At the same time, a circuit is established by the wire 12 from the binding post 6 through the normally closed ignition switch I and by wire 13 through the electrical resistance element 14 to the ignition transformer IT and from thence through wire 15 to wire 7 to complete the circuit. It is therefore seen that the closing of the motor switch energizes the ignition transformer to cause the igniter electrodes E to produce a spark, at the same time that the operation of the burner motor BM is initiated, to ignite the fluid fuel passing through the nozzle by operation of the motor BM. During the normal operation of the commercial system illustrated in Figure 1, the production of a flame in the burner nozzle will shunt the resistance heater RH of the safety switch.

The passage of the current through wires 12 and 13 which energize the electrical resistance heating element 14 causes the free end 19 of the bimetallic strip 16 to move toward the right, and as the rack 34 is in engagement with the tooth 27 this movement will rotate the carrier plate 20 to tilt the ignition switch to the open position, as shown in Figure 6 of the drawings. As the electrical resistance heater 14 is in series

with the ignition circuit, as soon as the ignition switch has been tilted to the open position the circuit through the heating element 14 is opened and as it cools the bimetallic strip 16 will cause its free end 19 to move to the left and as shown in Figure 7, the teeth of the rack 34 upon the actuator plate 32 will wipe over the tooth 27 of the carrier plate 20, which plate 20 is held in its rotated position by engagement 10 of the pawl 29 of the latch with the toothed segment 26 thereon. When the free end 19 of the bimetallic strip has returned the actuator plate 32 to the idle position shown in Figure 2, the ignition switch I is maintained in its open position, as shown in Figure 7.

During the normal operation of the heating system when the temperature of the room has been satisfied, the room thermostat opens and immediately the repulsion relay becomes de-energized and the secondary coil SC thereof drops to rest upon the stationary primary coil PC and causes the latch release 31 to engage the depending portion 30 of the latch to lift the pawl 29 out of engagement with the toothed segment 26 of the switch carrier plate and as this lifting of the latch causes the stud 36 thereon to engage the under edge of the slot 35 in the actuator plate 32 to lift the rack 34 out of engagement with the tooth 27 upon the carrier plate, the carrier plate is then free to rotate and tilt the ignition switch I to its closed position.

The duration of the ignition period, that is, the time between the initial closing of the circuit through the ignition switch until the movement of the end 19 of the bimetallic member 16 through the toothed rack 34 of the actuator plate 32 in engagement with the tooth 27 on the carrier plate rotates the carrier plate to open the ignition switch, may be adjusted by the knurled headed set screw 37 threaded through a post 38 between the front plate 18 and the base plate 22 in line with the left end 39 of the segmental portion 26 of the carrier plate 20 which will determine the position of the plate 20 when the ignition switch I is in its closed position.

It is therefore apparent that the ignition device described herein, provides for the immediate restoration of the ignition switch I to closed position with each opening of the motor switch M independent and irrespective of the operative condition of the bimetallic actuator 32, at the time, since the action of the latch release 30 while disengaging the pawl 29 from the teeth 26 also removes the actuator from operative engagement 55 with the tooth 27 mounted upon the ignition switch carrier. Thus, the ignition switch always returns to its starting position from which a full period of ignition begins upon reclosing the motor switch.

It is further seen that there is no delay required to allow the bimetal to cool to its cold position before operation can be resumed. Even with the maximum ignition period which may be provided with the adjustment 37, bimetal may be used which will provide a much greater range of movement than is utilized to open the ignition switch so that there may be a series of interruptions followed by a reclosing of the motor circuit by switch M, with the assurance that not less than a full period of ignition will be provided each time.

Of course, should the opening and closing of the motor switch be so frequent and numerous that the full movement of the bimetal has been obtained by continuous heating, the ignition

switch will remain closed in which case there will be continuous ignition until corrections in burner operations or a return to normal operations permits the bimetal to cool. In such instances of frequent interruptions accompanied by immediate resumptions of operation, the ultimate establishment, after a time, of continuous ignition may readily be considered desirable over the period of such operations.

What I claim is:

1. A control for electrical ignition means employed with electrically operated fluid fuel burners, a burner motor circuit including a control switch, electrically operated means for actuating said switch to open and closed position, an ignition circuit including an electrical ignition device therein, a switch normally urged to closed position connected in the ignition circuit energized through said burner control switch for the electrical ignition device, a normally inactive electro-thermal actuator rendered operative upon the closure of both the burner control and ignition switches, means rendered active by the electrical operated means upon closing the burner control switch to establish an operative connection between the electro-thermal actuator and closed ignition switch to cause the opening of the ignition switch by the thermal actuator after a predetermined movement of the actuator and thereafter hold the ignition switch open while the electro-thermal actuator returns to normal inactive position, said means, upon deenergization of the electrically operated means to open the main switch, adapted to remove the operative connection between the thermal actuator and ignition switch and release the ignition switch from its held open position to allow its immediate return to its normally closed position irrespective of the condition of the electro-thermal actuator.

2. A control for the electrical ignition means employed with electrically operated fluid fuel burners, a burner motor circuit including a control switch, electrically operated means for actuating said switch to open and closed position, an ignition circuit including an electrical ignition device therein, a switch with operating means normally positioning said switch in closed position and movable after a predetermined degree of movement to position said switch in open position said switch connected in the ignition circuit energized through said burner control switch for the electrical ignition device, an electro-thermal element having an electric heater in the ignition circuit controlled by the ignition switch, means, actuated by the thermal element, movable into and out of operative engagement with the ignition switch operating means, a latch actuated by the electrically operated means upon closing the burner control switch to allow said thermal actuated means to move into operative engagement with the ignition switch means to cause the opening of the ignition switch by the thermal element when heated and to hold the ignition switch when opened while the thermal element cools, said latch upon deenergization of the electrically operated means to open the burner control switch adapted to remove the thermally actuated means from operative engagement with the ignition switch operating means and release said switch from its held open position to allow its immediate return to its normally closed position.

3. An ignition control for an electrically op-

erated and controlled fluid fuel burning mechanism including a burner motor circuit, a switch in the burner motor circuit, electrically actuated means for opening and closing the motor switch and an ignition circuit having an electrical ignition device therein, a switch in the ignition circuit for the electrical ignition device connected in parallel to the motor circuit, said ignition switch normally urged to closed position, a thermal strip, an electrical resistance heater element controlled by the ignition switch energized upon the closing of the motor circuit associated with the thermal strip adapted to warp in response to heat and impart movement to its free end, an actuator plate pivotally mounted upon the said free end adapted to be reciprocated thereby, a pivoting carrier plate mounting the ignition switch, a tooth upon the carrier plate and a rack upon the actuator plate adapted to engage the tooth to rotate the carrier plate to open the ignition circuit upon movement of the actuator plate in one direction and as the strip cools to wipe over the tooth when traveling in the opposite direction.

4. The structure of claim 3, wherein said carrier plate is provided with a toothed segment upon its upper surface and wherein a pivoted latch is provided having a pawl adapted to ride over the toothed segment as the carrier plate moves the ignition switch to open position and engages the segment to prevent countermovement, said latch provided with a depending arm adapted to be engaged by a latch release when the motor switch opens to release the engagement of the latch with the carrier plate to allow the return of the ignition switch to open position.

5. An ignition control for an electrically operated and controlled fluid fuel burning mechanism including a burner motor circuit, a switch in the burner motor circuit, electrically actuated means for opening and closing the motor switch and an ignition circuit having an electrical ignition device therein, a switch in the ignition circuit for the electrical ignition device connected in parallel to the motor circuit, said ignition switch normally urged to closed position, a pivoted carrier plate mounting said ignition switch, an electrical resistance heater element connected in series with the ignition switch, a thermal strip secured at one end and responsive to the heating element to impart movement to the free end of the strip, an actuator plate carried by the free end of the strip, a tooth upon the side of the carrier plate, a rack upon the actuator plate arranged to engage the tooth to rotate the carrier plate upon movement in one direction and to wipe over the tooth upon reverse movement, a toothed segment upon the carrier plate, a pivoted latch having a pawl adapted to ride over the toothed segment as the plate is rotated to open the ignition switch and engage the toothed segment to prevent counter-rotation, a latch release operatively associated with the motor switch adapted to engage the latch when the motor switch opens to release the carrier plate to return the ignition switch to closed position, a slot in the actuator plate and a stud on the latch received therein and adapted to engage the actuator plate when the latch is released to lift the actuator plate out of engagement with the tooth on the carrier plate.

IRV E. McCABE.
